Patented May 14, 1918.

3 SHEETS—SHEET 3.

UNITED STATES PATENT OFFICE.

DAVID RUNYEN, OF GRAND RAPIDS, MICHIGAN, ASSIGNOR TO THE RUNYEN MANUFACTURING CO., OF GRAND RAPIDS, MICHIGAN, A CORPORATION OF MICHIGAN.

GREASE-DISPENSING MECHANISM.

1,265,961.

Specification of Letters Patent. Patented May 14, 1918.

Application filed June 15, 1917. Serial No. 174,920.

To all whom it may concern:

Be it known that I, DAVID RUNYEN, a citizen of the United States of America, residing at Grand Rapids, in the county of Kent and State of Michigan, have invented certain new and useful Improvements in Grease-Dispensing Mechanism; and I do hereby declare the following to be a full, clear, and exact description of the invention, such as will enable others skilled in the art to which it appertains to make and use the same.

This invention relates to a grease dispensing mechanism and has for its object and purpose the simplification of the construction and operation of grease dispensing devices whereby the same may be produced at a much lower cost than heretofore and, at the same time, the mechanism will be rendered more durable and efficient. For the attainment of these desired ends I have embodied my invention as disclosed in the accompanying drawings in which:

Figure 1 is a vertical section through one form of my invention.

Fig. 2 is a plan view thereof with parts broken away and shown in section.

Fig. 3 is an elevation, parts also being broken away and shown in section to disclose the interior structure.

Fig. 4 is a vertical sectional view substantially on the line 4—4 of Fig. 6, illustrating a slightly modified form of construction.

Fig. 5 is a side elevation of said modified form.

Fig. 6 is a plan view with parts broken away and shown in section and,

Fig. 7 is a fragmentary plan view also partly in section of the modified construction of cabinet.

Figs. 8, 9 and 10 are views similar to Figs. 1, 3 and 2 of a second modified form of construction of cabinet.

Like reference characters refer to like parts throughout the several views of the drawings.

The grease is adapted to be contained within a can or other suitable receptacle, preferably a cylindrical can 1 having a bottom 2 the upper end of the can being practically closed by a segment 3 permanently secured in place and to which a second segment 4 is pivotally connected to complete the closure of the upper end of the can and at

the same time permit the entrance of grease 55 therein.

The segment 3 carries a member 5 from the under side of which depends a ring 6 integral therewith. This ring passes through a suitable opening in segment 3. At each 60 side the member 5 is provided with integral ears 7 through which suitable bolts 8 pass to connect the member firmly to segment 3.

A barrel 9 is located within the can 1, its upper end entering loosely within the ring 65 heretofore described. In the lower part of the can a casting 10 is located on the upper side of which a conical tapered seat 11 is made against which the lower edges of the barrel 9 normally rest. The casting 70 10 has an extension 12 which passes through a side of the can 1 as shown and to which any suitable flexible hose conduit may be attached, a passage 13 in said casting and extension 12 thereto being made which communicates with the interior of the barrel 9. A pair of upwardly extending lips 14 are formed integral with the casting 10 and extend above the conical seat 11 for a short 75 distance into the lower end of the barrel. 80

A foot member including a horizontal base 15 with two separated vertical ears 16 is secured to the can by means of bolts 17 which pass through said ears and also through laterally extending parts to the casting 10 thereby rigidly connecting the casting in place at the same time that the foot member is secured in position. The extension 12 to the casting passes between the ears 16. A piston rod 18 is located within 90 the barrel 9 and passes through the member 5 its lower end carrying a suitable valveless piston 19 while its upper end is equipped with an operating handle 20. Between casting 10 and the inner side of the can 1 any 95 suitable gasket 21 may be located to prevent leakage of grease.

In operation, on the upward stroke of the piston the barrel 9 is raised until its upper end engages with the lower side of the 100 member 5 thereby leaving two openings between the lips 14 for the entrance of grease into the passage 13 and into the barrel as the upward stroke is continued. The lips 14 hold the lower end of the barrel from 105 disengagement with the casting 10 and on the downward stroke of the piston the barrel, at its lower end, seats tightly against

the conical seat 11 and the grease within the barrel and passage is forced outward through the extension 12 and any conduit that may be connected thereto.

5 The modification shown in Figs. 4 to 7 inclusive is similar in substantially all respects except that the extension 12 to the casting 10 shown in Fig. 1 is not passed through the side of the can as before but, as 10 shown in 12^a in Fig. 4, it is located within the can there being a tube 22 secured in the end of said extension and communicating with the passage 13, the upper end of the tube passing through the member 5^a which 15 is slightly modified in form from the member 5. Any suitable flexible hose connection to this tube may be made above the end of the can. This obviates the necessity of passing the part 12 through the side of the can and at the same time the foot member need 20 not be divided to make the two ears 16; but as shown in Fig. 5 the horizontal member 15^a has a single integral vertical section 16^a lying alongside the can and adapted to be 25 connected to the inner casting 10 by bolts 17 as before. The elimination of the outer extension 12 permits a better engagement of the foot with the horizontal foot portion 15^a. Otherwise the construction is identical 30 with that shown in Figs. 1 and 3 inclusive and the principle of operation is the same in both constructions.

In Figs. 8 to 10 inclusive a second and preferred modification is shown. In this 35 construction a base 23, of cast metal, is used to which the lower edges of the can 1 may be secured in any suitable manner, as by soldering. The base has depending annular sides 24 which serve to elevate the can a 40 short distance. A hollow projection 25 has an opening 26 in one side thereof the lower end of the barrel 9 passing over said projection and in its lowermost position seats against a conical tapered seat 27 similar to 45 the seat 11 heretofore described. The projection 25 has a stop for the downward thrust of the piston 19 whereby the piston rod 18^a may be of the same diameter throughout its 50 length. A passage 29 leads from the opening 26 to a point outside of the can terminating in an outwardly extending boss 30 in the upper side of which an opening is made whereby the tube 22^a may be threaded thereto. Integral also with the base foot are 55 ledges 31 one to each side of the boss 30. Of course, it is understood that while the tube 22^a may be secured as shown a hose such as indicated at 12^a may be connected either above or below the upper member 5^a which 60 is slightly modified from the members 5 and 5^a in the constructions previously described, so as to support the upper end of the tube 22^a.

The operation of the mechanism in this 65 construction is identical in practice with

that previously described but by it a single base casting may be utilized to take the place of the various parts 15, 16 and 17, 10 11, 12 and 14 of the construction shown in Fig. 1, precluding the necessity of making the holes in the can for passage of the screws 17, such screws being eliminated.

I claim:

1. In a device of the character described, a receptacle, a segment permanently secured to and partially closing the upper end of the receptacle, a cover hinged to said segment for completely closing the receptacle, a casting secured at the bottom of the receptacle below the segment, a lateral extension to the casting, a conical tapered seat on the upper side of the casting, there being a passage through the casting from the upper side within the limits of said seat and through said lateral extension, a tube secured to said extension, a member secured to the segment, an annular ring depending from said member through the segment, a barrel normally resting at its lower end on the tapered seat of the casting, and at its upper end entered a short distance into the ring, guiding means on the casting entering into the lower end of the barrel, a piston in the barrel, a rod connected thereto and extending through said member, an operating handle on the upper end of the rod, and a foot member located on the outside and at the bottom of the receptacle. 75 80 85 90 95 96

2. In a device of the character described, a receptacle, a segment permanently secured to and partially closing the upper end of the receptacle, a cover hinged to said segment, a member attached to the segment, a ring integral with the member on the under side thereof and passing through said segment, a casting secured at the lower part of the receptacle below said member, a lateral extension to the casting, a conical tapered seat formed on the upper side of the casting, said casting having a continuous 100 105 110 115 120 125 130 passage therethrough from the upper side within the limits of said seat and through the extension thereto, a conduit attached to said extension, a barrel loosely interposed between the member and casting normally resting at its lower end on the seat and at its upper end extending a short distance into the ring, a guiding device on the casting projecting into the lower end of the barrel, a piston in the barrel and means for reciprocating the piston. 130

3. In a device of the character described, a receptacle, a member permanently secured at the upper end of the receptacle, a ring depending from said member, a casting having a lateral extension secured at the bottom of the receptacle below the member, said casting having a passage opening at the upper side of the casting and extending through said extension, a tapered seat on 130

the upper side of the casting around the opening to said passage, a barrel loosely positioned between the casting and member with its lower end normally resting on the 5 seat and with its upper end extending a short distance within the ring, a piston in the barrel, means to reciprocate the same, and a conduit attached to the extension to the casting, substantially as described.

10. 4. In a device of the character described, a receptacle, a member permanently secured adjacent the upper end of the receptacle, a casting having a passage therethrough secured at the lower end of the receptacle, a 15 tapered conical seat around the opening to the passage, a barrel within the receptacle having its lower end normally seating against said seat and its upper end guided by the member, a conduit leading away from 20 the casting, a piston within the barrel, means to reciprocate the same, and means to limit upward movement of the barrel on the upward stroke of the piston, substantially as described.

25. 5. In a device of the character described, a receptacle, a member permanently secured adjacent the upper end of the receptacle, said member having a depending annular ring, a casting secured to the receptacle adjacent the bottom thereof and below said member, said casting having a passage there-

through and a tapered seat around one end of the passage, a barrel loosely mounted between the member and casting, its lower end normally seating against the tapered seat 35 and its upper end normally entering the ring for a short distance, a piston within the barrel, and means to reciprocate the piston, substantially as described.

6. In a device of the character described, 40 a receptacle, a member permanently secured adjacent the upper end of the receptacle, said member having a depending annular ring, a casting secured to the receptacle adjacent the bottom thereof and directly below 45 said member, said casting having a passage therethrough, a tapered conical seat on the casting around one opening of the passage, said seat extending downwardly and outwardly from the upper side of the 50 casting, a barrel interposed loosely between the casting and said member, the lower end of the barrel normally seating against said seat, with the upper end of the barrel entered a short distance into said ring, a piston 55 in the barrel, means to reciprocate the piston, and means on the casting associated with the lower end of the barrel to hold the barrel against disengagement from the casting on the upward stroke of the piston. 60

In testimony whereof I affix my signature.
DAVID RUNYEN.
